UNITED STATES PATENT OFFICE.

KEIJIRO NISHIO, OF TOKYO, JAPAN.

MACHINE FOR TAKING OUT GEOLOGICAL SAMPLES.

Application filed April 23, 1925. Serial No. 25,458.

To all whom it may concern:

Be it known that KEIJIRO NISHIO, subject of the Emperor of Japan, residing at No. 51 Sendaigi-cho, Hongo-ku, Tokyo, Japan, ⁵ has invented certain new and useful Improvements in Machines for Taking Out Geological Samples, of which the following is a specification.

This invention relates to a machine for ¹⁰ taking out geological samples and consists of a clamping base for a sample tube of a geological sampler, a receiver arranged in continuance to the sample tube and a piston for pushing out the contents of the tube, the ¹⁵ piston and the receiver being moved in the same direction with the same speed longitudinally along the in and out sides of the tube.

The object of the invention is to remove ²⁰ a sample from the sampler tube without compressing or confusing each stratum of the sample so that an accurate sample can be obtained.

In the accompanying drawings:

²⁵ Fig. 1 is a front elevation,
Fig. 2 is a side view taken from left,
Fig. 3 is a similar view taken from right,
Fig. 4 is a front elevation, the geological sample being taken out,

³⁰ Fig. 5 is a longitudinal sectional view of a sampling tube in case of obtaining a sample.

Like symbols refer to like parts in the drawings.

With reference to the drawings, a frame ³⁵ *b* is mounted on a base *a* at several intermediate portions and is provided with set screws *c* at top and sides, so that a sample tube *g* of a geological sampler is rigidly clamped when introduced. On the base, a bearing *d* is oppositely arranged in which a shaft *e* is journalled. The shaft is provided with a fly wheel *f* having a handle *f* at the extreme end and a pinion *h* at the middle. The pinion is arranged to gear a rack *i* ⁴⁰ which is attached to a piston at one end, said piston being slidably fitted in the tube. A receiver *l* of semi-circular form is mounted longitudinally and is movable along the tube which is laid horizontally. The receiver *l* is provided with several legs *m* ⁴⁵ which are respectively fitted with small rollers *o*. These legs are relatively connected to each other by means of a connecting bar *n*. The bar is at its extreme end ⁵⁰ fixed to a free end of the rack *i* so that the

receiver *l* is longitudinally moved together with the rack *i*. For this purpose, a rail *p* is mounted on the base *a* as a guide for the rollers *o*.

By turning the handle *f*, the fly wheel is ⁶⁰ driven to revolve the pinion which drives the rack *i* to right together with the connecting bar *n*, so that the receiver is transmitted to right in same speed to that of the piston *k*. ⁶⁵

For application of the present example, the sample tube *g* stuffed with a geological sample is brought into the frame and clamped therein by three set screws *c* in such a relation that the piston *k* is to be introduced in the tube from one end. Then, the handle *f* is turned whereupon the piston *k* ⁷⁰ proceeds in the tube *g* to push out the sample *r*. The sample is progressively removed from the tube *g* and is received in the receiver *l* while the same is longitudinally moved. ⁷⁵

The invention is characterized by that the receiver, as above described, proceeds progressively receiving the portion of the sample pushed out from the tube, so that the sample received in the receiver is never damaged to confuse its stratum or compressed to change its length. Contrary, if the sample tube stand vertically for taking out the sample, each stratum may be deformed and confused and especially when it was obtained from slushy and sandy earth, no accurate stratum can be obtained. Or, if the receiver is not removed horizontally when ⁸⁰ the sample is pushed out, a portion of the sample which is initially pushed out may be slid along the receiver by the successive portion of the sample until the former portion thereof increases its own mass, so that there may occur a stoppage of the piston by the frictional resistance between the mass and the surface of the receiver. If further discharge is compelled successive portions of ⁸⁵ the sample are greatly compressed so that the length of the sample will be shortened from the actual one. However, in the present invention, the sample has little tendency to be shortened in the course of compression of the piston, because the sample is not loosely plunged out of the tube owing to the resistance between the wall of the tube and the sample itself. The reduction of the sample, if any, can be corrected by a certain reasonable calculation. ⁹⁰ ⁹⁵ ¹⁰⁰ ¹⁰⁵ ¹¹⁰

What is claimed is:—

1. A machine for taking out a geological sample from a sample tube, comprising a device to support the sample tube horizontally, a receiver arranged in continuance to the sample tube and a piston to push out the sample from the tube, the piston and receiver being moved or propelled in the same direction with the same speed longitudinally along the in and out sides of the tube, substantially as shown and described.

10 2. A machine for taking out a geological sample from a sample tube, comprising a device to support the sample tube horizon-

tally, a receiver arranged in continuance to 15 the sample tube and a piston to push out the sample from the tube, the piston and receiver being moved or propelled in the same direction with the same speed longitudinally along the in and out sides of the 20 tube, in which the piston rod is provided with a rack geared with a pinion and the receiver is of semi-circular form having legs for sliding upon a rail, the piston rod and receiver being interconnected with a rod, 25 substantially as shown and described.

In testimony whereof I affix my signature.

KEIJIRO NISHIO.
